DESIGN FOR A LOCKET OR SIMILAR ARTICLE

Edward T. Krol, Sacramento, Calif.

Application February 2, 1943, Serial No. 109,410

Term of patent 3½ years

To all whom it may concern:

Be it known that I, Edward T. Krol, a citizen of the United States, residing at Sacramento, in the county of Sacramento and State of California, have invented a new, original, and ornamental Design for a Locket or similar article, of which the following is a specification, reference being had to the accompanying drawing, forming a part thereof.

Figure 1 is a side elevational view, showing one side face of a locket embodying my new design.

Figure 2 is an elevational view, showing the opposite side face thereof.

Figure 3 is an edge elevational view thereof.

I claim:

The ornamental design for a locket or similar article, as shown.

EDWARD T. KROL.
